UNITED STATES PATENT OFFICE.

NICHOLAS J. KLEIN AND JAMES C. LAW, OF SCRANTON, PENNSYLVANIA ASSIGNORS TO
WILMOT ENGINEERING COMPANY, OF HAZLETON, PENNSYLVANIA, A CORPOR-
ATION OF PENNSYLVANIA.

CHAIN.

Application filed July 19, 1923. Serial No. 652,567.

To all whom it may concern:

Be it known that we, NICHOLAS J. KLEIN and JAMES C. LAW, citizens of the United States, and residents of Scranton, in the 5 county of Lackawanna and State of Pennsylvania, have invented an Improvement in Chains, of which the following is a specification.

In the use of power chains as conveyors, 10 particularly in connection with the handling of coal, or for other purposes, the pintles by means of which the links are pivotally connected as well as the portions of the links with which the pintles engage become 15 worn so that the pitch of the chain is altered which interferes with the satisfactory operation of the chain.

One of the objects of our invention is to provide novel means whereby after the 20 portions of the chain structure, as above indicated, have become worn the defect thus brought about may be to a large extent overcome and eliminated.

A further object of the invention is to 25 provide a chain of novel construction comprising means whereby adjacent links may be more readily connected with and disconnected from each other than heretofore has been practical in so far as we are aware.

30 A further object of the invention is to provide a chain of novel construction which is simple in its structure and relatively very strong and durable.

We shall not undertake at this point to 35 point out all of the various objects and advantages of our invention, but other and further objects will be pointed out in the detailed description thereof which follows or will be apparent from such description.

40 In order that the invention may be readily understood and its practical advantages fully appreciated, reference may be had to the accompanying drawing in which we have illustrated a convenient form of embodiment thereof. However, it will be understood that changes in the details of construction may be made within the scope of the claims without departing from our invention.

45 In the drawing:

Fig. 1 is a side elevation of a section or portion of chain constructed in accordance with our invention;

50 Fig. 2 is a view partly in top plan and partly in horizontal section;

Fig. 3 is an enlarged view of a fragmentary portion of a chain structure embodying our invention and in which the wear of the pintle and the portions of the ends of the chain links in engagement therewith are shown;

Fig. 4 is a horizontal sectional view taken on the line 4—4 of Fig. 3 in which the wear of the said parts is more clearly shown;

Fig. 5 is a view similar to that shown in 65 Fig. 3 but with the pintle shown in reversed position;

Fig. 6 is a horizontal sectional view taken on the line 6—6 of Fig. 5;

Fig. 7 is a perspective view of a pintle 70 with the heads thereon before the same has been used; and

Fig. 8 is a view in side elevation of one end portion of a chain link indicating by dot and dash lines the wear effected by the 75 frictional contact between a pintle and the said link.

Referring to the drawing: 1 and 2 designate the side bars of chain links which are arranged alternately with respect to single 80 links 3. The said side bars constitute alternate double links of the chain and each side bar is provided with openings, as indicated at 4, the outer ends of which openings are circular, as indicated at 5. As indicated in the drawing the openings 4 are separated from each other but it will be understood that the said openings may be shorter than shown or they may be extended so as to join each other and thereby constitute a single opening. Each of the side bars 1 and 2 is also provided with an inwardly extending projecting or enlarged portion 6. In other words, the central portions of the side bars 1 and 2 are thinner 85 than the outer end portions thereof. The inwardly extending thickened portions of the outer ends are joined to the inner surfaces of the central portions of the said side bars by means of inclined shoulder portions, as 90 indicated at 7.

The side bar 1 is provided with lugs 10 and 11, the lug 10 being situated adjacent the right hand end of the said bar and also adjacent the bottom edge thereof, while the lug 11 is situated adjacent the left hand end thereof and adjacent the upper edge thereof. The side bar 2 is provided with lugs 12 and 13, the former being situated adjacent the right hand end of the said 105 110

bar and adjacent the upper edge thereof, while the latter is situated adjacent the left hand end thereof and adjacent the lower edge. It will be observed, therefore, that 5 the lugs 10 and 11 are situated in reverse position with respect to the lugs 12 and 13.

The alternate single links 3 are slotted, as indicated at 15, and the opposite ends of the said slots are circular, as indicated at 10 16. The adjacent overlapping ends of the single and double links are adapted to be pivotally connected together by means of pintles 20 which are of cylindrical form. The said pintles are provided with heads 21 15 which may be described, it is believed, with sufficient accuracy as being of rectangular shape.

Each of the heads 21 is provided with a notch or cut-away portion, as indicated at 20 25. The cut-away portion or notch 25 in the edge of one of the said heads is situated adjacent one end thereof, while the cut-away portion or notch in the other of said heads is situated at the opposite end thereof. In 25 other words, the cut-away portions are situated in diagonal relation with respect to each other. This arrangement is provided, for example, in order that when the chain is new the lug 10 (see Fig. 2 of the drawing) 30 may occupy a position in one of the said notches, while the lug 12 (see Fig. 1 of the drawing) will at the same time occupy a position in the other of said notches or cut-away portions.

35 This is the relative position occupied by the heads of the pintles and the lugs when the chain is new and when the pindle is of cylindrical form. It will be noted that the opposite sides 30 of the respective heads are 40 straight and are not provided with notches or depressions of any kind or character whatsoever.

As already intimated, the pintles, when new, are of cylindrical form, as is indicated 45 in Figs. 1 and 2 of the drawing.

50 After the chain has been used for a period of time, the length of which depends upon conditions of use, the pintles become worn as do also the circular end portions of the slots 4 and 5 of the side bars 1 and 2 of the double links and the slot 16 of the single links 3. The wear of the pintles is clearly indicated in Figs. 3 and 4 of the drawing. Such wear is best shown perhaps 55 in Fig. 4. It will be seen that the portion of the pindle which is in engagement with the single link 3 is worn down so as to form shoulders as indicated at 31. The opposite side of the central portion of the pindle remains unworn, as indicated at 32. The opposite end portions of the pintles which are 60 in engagement with the outer ends of the slots 4 of the side bars 1 and 2 of the double link are worn down so as to form shoulders 65 33. The portions 34 of the said pintles op-

posite the worn down portions thereof are unaffected. It will be understood also that the portions of the links which are in contact with the pintles are likewise worn. We have undertaken to indicate the amount of 70 this wear in connection with the side bar 2 by the dash and dot line 35 in Fig. 8.

It will be understood that after a chain has been used until the pintles and the links have become worn, as indicated in Figs. 3 to 75 6 and 8, the pitch becomes different from what it was originally or when new, so that the satisfactory operation of the chain is somewhat interfered with. In order to restore to a very considerable extent the 80 chain to its original condition the pintles are turned through angles of one hundred and eighty degrees so that the straight sides or edges 30 of the heads 21 are turned into position to contact with the outer edges or 85 ends of the lugs 10, 11, 12 and 13 of the side bars 1 and 2 of the respective double links. By thus turning the pintles the unworn portions 32 thereof are placed in contact with the outer ends of the slots of the single links 90 3, while the unworn portions 34 are placed in contact with the outer ends of the slots 4 in the side bars 1 and 2 of the alternate double links.

95 By positioning the lugs 10 and 11 and 12 and 13 upon the side bars 1 and 2, as shown, the pintles are prevented from turning with respect to the side bars 1 and 2 of the double links and thereby are prevented from being accidentally displaced or removed from the 100 slots with which they are engaged. In other words, the heads 21 are held in transverse relation to the slots 4 of the side bars 1 and 2. For the purpose of turning the pintles from the position shown in Figs. 1 to 4 to 105 the positions shown in Figs. 5 and 6 the adjacent links are adjusted with respect to each other so that the thickened portions 6 are carried beyond the shoulders of the 110 single links 3 or, in other words, the relative positions of the overlapping end portions of the bars 1 and 2 and the single links 3 are changed so that the enlarged end portion of the single link occupies a position 115 between the relatively thin portions of the side bars 1 and 2. This permits the side bars to be moved toward each other. When the bars are moved or adjusted to their innermost position the vertical distance between the planes including the outer sides of the 120 lugs 10 and 12, for instance, is less than the distance between the inner surfaces of the heads 21. It is apparent that when the side bars are in this position the pindle may be turned to reverse or change its position as 125 above described.

To remove a pindle for the purpose of disconnecting any two adjacent links of the chain the links are collapsed longitudinally and laterally to permit the turning of the 130

pintles into positions so that the heads 21 thereof extend longitudinally with respect to the slots 4 and 15. When in this position the heads may be passed through the said slots and the pintles removed. In similar manner the links may be connected, the only difference in the operation being that the pintles are inserted through the said slots instead of being removed therefrom.

10 Having thus described our invention, what we claim and desire to secure by Letters Patent is:

1. A chain comprising alternate single and double links having slots extending horizontally therethrough adjacent their opposite ends, each of the said bars of each double link being provided with outwardly extending projections, one projection being situated near one end adjacent one edge thereof and the other projection being situated near the opposite end adjacent the opposite edge thereof, and pintles extending through said slots and pivotally connecting the links together, said pintles each having heads upon their opposite ends for retaining said pintles in engagement with said links, each head having a notch in one of its edges at one end thereof.

2. A chain comprising alternate single and double links, the said links having slots extending horizontally therethrough, each side bar of each double link being provided with an outwardly extending projection near each end, one of said projections being adjacent one edge thereof and the other of said projections being adjacent the opposite edge thereof, and the projections at the opposite ends of one of the said bars being in reverse position with respect to the projections of the other of said bars of each link, and pintles extending through said slots for pivotally connecting the links of said chain together, each of said pintles being provided with heads at its opposite ends for retaining the same within said slots which heads are each provided with a notch in one edge at one end thereof, the end of one head in which the notch is provided being oppositely related to the end of the other head in which the notch is provided.

3. A chain comprising alternate single and double links, each of which is provided with slots extending therethrough adjacent their opposite ends and each of the side bars of each double link being provided with an outwardly extending projection near each end, one projection being situated adjacent one edge and the other projection being situated adjacent the opposite edge, and pintles extending through said slot, each of which pintles is provided with heads at its opposite ends for retaining the said pintles in place within said slots, and each of the said heads being provided with a notch in one edge adjacent one end thereof, the said

notches being situated in diagonal relation with respect to the axes of the respective pintles.

4. A chain comprising alternate single and double links, which links are each provided with slots extending horizontally therethrough and the said single links terminating in enlarged head-like portions and the side bars of each of the double links being provided with enlargements upon their inner sides adjacent their opposite ends, the said enlargements being adapted to overlap the head-like portions of the said solid links, and the said side bars of the respective double links being adapted to be moved or adjusted toward each other when the said single and double links are collapsed longitudinally with respect to each other, and the side bars of each double link being provided at each end with an outwardly extending projection, the projection upon one side bar of each double link being in reverse position with respect to the projections upon the opposite ends of the opposite side bar of said link, and pintles situated in the said slots, which pintles are provided with heads at their opposite ends for retaining the said pintles within said slots, each of said heads being provided with a notch in one edge at one end thereof, and one end of one head of each pintle being adapted to contact with a projection upon one of the said side bars and the opposite end of the opposite head being adapted to contact with the reversely situated projection upon the opposite side link.

5. A chain comprising alternate single and double links, said links each having slots adjacent their opposite ends for the reception of pintles for pivotally connecting said links, each of the side bars of each double link being provided with an outwardly extending projection near each end, one projection being adjacent one edge and the other projection being adjacent the opposite edge, and the projections upon one side bar of each double link being in reverse position with respect to the projections upon the other side bar, and the said pintles, which pintles are provided with heads at their opposite ends, one head of each pintle being provided with a notch in one edge adjacent one end and the other head being provided with a notch at its opposite end in the corresponding edge, one of the said notches being adapted to engage one of the said projections at one end of the end bar of the double link, and the other of said notches being adapted to engage the reversely positioned projection of the opposite side bar of the link.

6. A chain comprising alternate single and double links, said links being provided with slots extending horizontally therethrough, the side bars of each double link

being provided with an outward projection near each end, one of said projections being adjacent one edge and the other of said projections being adjacent the opposite edge 15 and the projections upon one side bar of each double link being situated in reverse position with respect to the projections upon the opposite side bar, and pintles situated within said slot for pivotally connecting the said links together, said pintles each being provided with heads at their opposite ends, each of which heads is provided with a notch in one edge adjacent an end thereof, the said notches being situated in diag-

onal relation with respect to the axis of the 20 pintle, and the said notches being adapted to engage the said projections, and the said pintles being adapted to be turned through angles of one hundred and eighty degrees whereby the opposite unnotched sides of 25 said heads are adapted to contact with said projections.

In testimony that we claim the foregoing as our invention, we have hereunto signed our names this 9th day of July, 1923.

NICHOLAS J. KLEIN.
JAMES C. LAW.
